APRON RETORT CRATE LOADER

Filed March 20, 1931

Inventor,
M. S. Canaday
By Fred G. Gandy, his
Attest.

UNITED STATES PATENT OFFICE

MIRON S. CANADAY, OF ROCHESTER, MINNESOTA, ASSIGNOR TO REID, MURDOCH & CO.,
OF CHICAGO, ILLINOIS, A CORPORATION OF ILLINOIS

APRON RETORT CRATE LOADER

Application filed March 20, 1931. Serial No. 523,968.

This invention relates generally to a loading means for a retort crate and more particularly to an apron and supporting structure for loading cans into retort crates.

a large hem 6 along one edge which is adapted to slip over a horizontally extending curved pipe 7 which is supported adjacent the discharge end of a conveyor designated generally at 8. The pipe 7 is secured to the upper ends of a pair of adjustable standards 9 by means of short horizontal pipes 10, this supporting structure being positioned at the end of the conveyor which carries the filled cans away from a closing machine.

5 In canning and preserving it is general practice to place a load of filled cans in a crate which is suspended from an overhead carrier or hoist and adapted to be lowered into a retort while the goods in the cans are being processed, and then lifted out of the retort

55 upon the completion of the processing. A crate for this use may be of the construction disclosed in my copending application Serial No. 456,853 filed May 29, 1930.

10 An object of the present invention is to provide a new and improved apron loader for such retort crates adapted to be positioned at the end of a conveyor which removes the cans from the closing machine, and which 15 serves as a means for loading the cans into a crate.

A cylindrical crate 11 of the type disclosed in said prior application is positioned on the floor beneath the apron 5 as illustrated diagrammatically in the drawings, and in order to span the apron across the top of the crate, means is provided at the front edge of the apron for securing the apron to the crate. As illustrated herein, this means comprises a metal rod 12, which is secured along the front edge of the apron by means of suitable leather reinforcing, and has a handle 13 at its central portion. The ends of the rod are preferably bent to form hooks 14 which are adapted to slip over the side of the retort crate 11 to secure the apron thereto in a spanned condition.

20 Another object is to provide such an apron of novel construction which will enable an operator to direct the cans into a crate and 25 to control the placing of the cans in any part of the crate without denting or jamming them.

25 A further object is to provide such an apron having a central opening therein through which the cans may drop, together with a tubular part of flexible material extending 30 downwardly from said opening and forming a discharge spout which serves as a buffer for the cans to prevent injury thereto, and which 35 may be swung sidewise at its lower end to direct cans into any part of the crate.

35 Further objects and advantages of the invention will become apparent from the following detailed description taken in connection with the accompanying drawings, in which:

Fig. 1 is a plan view of a preferred form of the invention.

Fig. 2 is a side elevation thereof showing the exemplary form of the invention positioned in operative relation to the discharge end of a conveyor.

In the form illustrated in the drawings, the invention comprises a heavy canvas apron 5 somewhat rectangular in form and having

40 a spiral guide device 15 is provided through which the upstanding cans on the conveyor 8 pass. This device turns the cans so that they roll onto the apron. Cans 45 which are thus discharged onto the apron from the conveyor roll towards the center of the apron which has a somewhat oval opening 16 therein through which the cans may pass. A flexible canvas tube 17 has its upper 50 edge secured along the edge of said opening by leather reinforcing 18, and extends downwardly to form a discharge spout through which the cans pass into the crate. The sides of this tube serve as a buffer for 55 the cans rolling through the opening 16 and in order to enable an operator to direct the cans into all parts of the crate, a plurality of leather strap handles 19 are preferably secured to the outside of the tube adjacent its 60 lower end. These may be grasped by the operator to swing the lower end of the tube laterally in the crate. To close the lower end of the tube while a filled crate is being replaced with an empty one, a ring 20 may be secured 65

to one side of the tube and a snap 21 to the other.

As illustrated most clearly in Fig. 1, the apron 5 is preferably provided with laterally extending side portions 22 to increase the area thereof adjacent the opening 16, and a leather reinforcing member 23 is secured to the canvas apron to cover the portion onto which the cans are dropped from the conveyor.

The invention provides a simple and readily operable device for receiving cans from a conveyor and loading them into retort crates, and is constructed so as to enable an operator to direct the cans into all parts of the crate by swinging the lower end of the flexible tube 17 laterally of the crate. The free end of the apron may be readily detached from a loaded crate and attached to the succeeding empty one, and the standards 9 may be adjusted for the purpose of properly positioning the apron relatively to the discharge end of the conveyor.

Having thus described the invention, what I claim as new and desire to secure by Letters Patent, is:

1. A device of the character described comprising, in combination, a pair of supporting standards having a transversely extending member secured intermediate their upper ends and adapted to be positioned adjacent the end of a conveyor, an apron attached along one edge to said transversely extending member and adapted to extend horizontally from the end of the conveyor for receiving cans discharged therefrom, means secured along the opposite edge of the apron adapted to slip over the side of a crate to span the apron across the crate, said apron having an aperture through which the cans received thereon may pass and a member of flexible material having its upper edge secured to the apron along the edge of said opening and extending downwardly into the crate to form a buffer for the cans.

2. A device of the character described comprising, in combination, a pair of supporting standards having a transversely extending member secured intermediate their upper ends and adapted to be positioned adjacent the end of a conveyor, an apron having means along one edge for securing the apron to said transversely extending member and adapted to extend horizontally from the end of the conveyor for receiving cans discharged therefrom, a rod secured along the opposite edge of the apron having end portions bent downwardly to form hooks adapted to slip over the side of a crate so as to span the apron across the crate, said apron having a substantially central aperture through which the cans received thereon may pass, a tube of flexible material having its upper edge secured to the apron along the edge of said opening and extending downwardly into the crate, and a plu-

rality of strap handles secured to the outside of said flexible tube to enable an operator to swing the lower portion of the tube to direct cans into any part of the crate.

3. A device of the character described comprising, in combination, a pair of adjustable supporting standards having a transversely extending curved member secured intermediate their upper ends and adapted to be positioned adjacent the end of a conveyor, an apron having a hem along one edge for securing the apron to said transversely extending member and adapted to extend horizontally from the end of the conveyor for receiving cans discharged therefrom, a rod secured along the opposite edge of the apron having a central portion forming a handle and end portions bent downwardly to form hooks adapted to slip over the side of a crate, said apron having a central oval aperture through which the cans received thereon may pass, a tube of flexible material having its upper edge secured to the apron along the edge of said opening and extending downwardly into the crate, a plurality of strap handles secured to the outside of said flexible tube to enable an operator to swing the lower portion of the tube to direct cans into any part of the crate, and means for closing the lower end of the tube while a filled crate is being removed and an empty crate placed in position.

4. An apron crate loader comprising, in combination, a flexible apron adapted to be attached along one edge to a supporting member, a member secured along the opposite edge and having a plurality of attaching devices secured thereto for spanning the apron across the top of a crate, said apron having an opening therein and a flexible tube having its upper end secured along the edge of said opening so as to provide a downwardly extending spout through which cans discharged onto the apron may pass and swingable to direct cans to various parts of the crate.

5. An apron retort crate loader comprising, in combination, a flexible apron having a hem along one edge for receiving a supporting member, a member secured along the opposite edge and providing a handle at its central portion, a plurality of attaching devices along said opposite edge of the apron for spanning the apron across the top of a retort crate, said apron having an opening therein and a canvas tube having its upper end secured along the edge of said opening so as to provide a downwardly extending spout through which cans discharged onto the apron may pass.

6. An apron retort crate loader comprising, in combination, a heavy canvas apron having a hem along one edge for receiving a supporting member, a rod secured along the opposite edge and having a handle at its central portion, a plurality of attaching devices along said opposite edge of the apron for

spanning the apron across the top of a retort
crate, said apron having an opening therein, a
canvas tube having its upper end secured
along the edge of said opening so as to pro-
vide a downwardly extending spout through
5 which cans discharged onto the apron may
pass, and a plurality of leather strap handles
secured on the outside of said tube adjacent its
lower end to facilitate directing cans to vari-
ous parts of a crate.

10 Signed at Rochester, Minnesota this 14th
day of March, 1931.
